UNITED STATES PATENT OFFICE.

FRANK WILSON LAMBERT, OF HANCOCK, IOWA.

PROPELLER.

1,422,109.

Specification of Letters Patent. Patented July 11, 1922.

Application filed October 21, 1921. Serial No. 509,356.

To all whom it may concern:

Be it known that I, FRANK WILSON LAMBERT, a citizen of the United States, residing at Hancock, in the county of Pottawattamie and State of Iowa, have invented certain new and useful Improvements in Propellers, of which the following is a specification.

This invention relates to improvements 10 in propellers and while designed primarily for embodiment in aircraft, may be employed with equal advantage for marine propulsion.

The primary object of the present invention is to provide a propeller which will act 15 with greater efficiency against the medium in which it is rotated and will therefore better serve its purpose and enable the craft upon which it is installed, to be propelled 20 more readily and forcibly and at a higher rate of speed and with a more economical consumption of fuel.

Briefly described, the present invention comprises a hub, blades which radiate from 25 the hub and which are of the form usually employed for propelling aircraft, and other blades which are supported at the outer ends of the first mentioned blades and are circumferentially disposed, and another im- 30 portant object of the invention is to so form the working surfaces of the last mentioned blades as to adapt these blades to compact the ambient fluid, whether it be air or water, and thus increase the resistance offered 35 and correspondingly increase the propelling force created through rotation of the propeller.

Another object of the invention is to form 40 the outer circumferential blades of the propeller of such contour as to adapt these blades to more readily cleave the ambient fluid and assist in the formation of a compressed bank of the fluid in rear of the propeller to offer the desired resistance.

45 In the accompanying drawings,

Figure 1 is a rear elevation of a propeller constructed in accordance with the present invention;

Figure 2 is a side elevation of the propeller;

Figure 3 is an end elevation thereof;

Figure 4 is a sectional view taken substantially on the line 4—4 of Figure 1 looking in the direction indicated by the ar- 55 rows;

Figure 5 is a similar view on the line 5—5 of Figure 1 looking in the direction indicated by the arrows;

Figure 6 is a similar view on the line 6—6 of Figure 1 looking in the direction 60 indicated by the arrows.

The propeller embodying the present invention comprises a hub 1 which is constructed in any suitable manner adapting it for mounting upon the propeller shaft, and 65 blades 2 radiate from the hub 1 and are provided with working faces 3 and advancing edges 4 which are given the required contour to adapt these blades to exert a propelling force in the operation of the propeller, the contour of these blades being substantially that of the ordinary propeller blades employed upon aircraft.

The blades 2 support at their outer ends 70 circumferential blades which are indicated 75 in general by the numeral 5. These blades 5 are termed circumferential for the reason that, generally speaking, they extend on arcs which are concentric to the axis of the hub 1. Each of these blades 5 has a working face which is indicated in general by the numeral 6, the opposite face of each blade indicated by the numeral 7, being how- 80 ever inactive. In addition to being disposed circumferentially with relation to the axis 85 of the hub 1, the blades 5 are disposed dia- 90 ginally with relation to said axis, and as regards this latter disposition, they are non- correspondingly placed so that one blade will be diagonal in one direction and the other blade diagonal in the opposite direc- 95 tion. Upon the working face 6 of each 100 blade 5 there is formed a fin which is indicated by the numeral 8. The advancing end of each blade 5 is indicated by the 105 numeral 9 and the opposite or following end by the numeral 10, and by reference to the several figures of the drawings it will be observed that the working face 6 is trans- versely concave from end to end, the fin 8 being relatively shallow and merging at one 110 end with the body of the blade 5 substan- tially at the advancing end 9 thereof and be- ing increased gradually in width and thick- ness from this end to the opposite end 10 of the said blade. Likewise the fin 8 is gradu- ally curved in an increasing degree from its first to its last mentioned end so that the working face 6 is gradually transversely curved at the advancing end 9 of the blade 110

and the degree of curvature is gradually increased towards the opposite or following end of the blade where it becomes very pronounced. Thus a pocket is formed by the 5 working face of the blade increasing in depth from the advancing to the following ends of the blade, and as the propeller is rotated, this pocket will collect the ambient fluid and compact the same and deliver the 10 compacted fluid in a manner to provide a bank thereof immediately in rear of the propeller.

The circumferential outer edge of each blade 5 or in other words that portion of 15 each blade which is located substantially at the line of juncture of the fin 8 with the working face of the blade, is formed with a longitudinally extending channel 11 relatively narrow and shallow at the advancing edge 20 9 of the blade and increasing in width and depth in the direction of the following end of the blade, principally for the purpose of rendering the propeller lighter in weight.

Having thus described the invention what 25 is claimed as new is:

1. A propeller comprising a hub, a blade radial thereto and having a surface contour adapting it to exert a propelling force in

action, and a circumferential fluid compression blade carried at the outer end of the 30 radial blade and disposed diagonally to the axis of the hub, the working surface of the last mentioned blade being relatively gradually transversely curved at the advancing end of the blade and of gradually increasing 35 transverse curvature in the direction of the hub and of the blade.

2. A propeller comprising a hub, a blade radial thereto and having a surface contour adapting it to exert a propelling force in 40 action, a circumferential fluid compression blade carried at the outer end of the radial blade and disposed diagonally to the axis of the hub, the last mentioned blade being provided upon its working face with a 45 curved fin one side of which merges with and constitutes a continuation of the working face of the said blade, the working surface being relatively gradually transversely curved at the advancing end of the blade 50 and of gradually increasing degree of transverse curvature in the direction of the following end of the blade.

In testimony whereof I affix my signature.

FRANK WILSON LAMBERT. [L.S.]
